CLAIM

The ornamental design for a golf club head, as shown and described.

DESCRIPTION

FIG. 1 is a bottom perspective view of a golf club head showing my new design;

FIG. 2 is a bottom view thereof;

FIG. 3 is a rear view thereof;

FIG. 4 is a toe end view thereof;

FIG. 5 is a heel end view thereof;

FIG. 6 is a front view thereof; and,

FIG. 7 is a top view thereof.

The uneven broken lines immediately adjacent to the shaded area represent unclaimed boundaries and form no part of the claimed design. The remaining uneven broken lines are shown for the purpose of illustrating environmental structure and form no part of the claimed design.
